UNITED STATES PATENT OFFICE

105,844

DESIGN FOR A COMBINED RADIO AND PHONOGRAPH CABINET

Donald Deskey, New York, N. Y.

Application May 10, 1937, Serial No. 69,256

Term of patent 7 years

To all whom it may concern:

Be it known that I, Donald Deskey, a citizen of the United States and a resident of New York city, in the county and State of New York, whose post-office address is No. 630 Fifth Avenue, New York city, New York, have invented a new, original, and ornamental Design for a Combined Radio and Phonograph Cabinet, of which the following is a specification, reference being had to the accompanying drawing, forming part thereof.

In the drawing:

Figure 1 is a perspective view of the cabinet in closed position, and

Figure 2 is a similar view with the closures of the cabinet in opened position.

One end wall and the back of the cabinet are flat and substantially rectangular in formation.

I claim:

The ornamental design for a combined radio and phonograph cabinet, as shown and described.

DONALD DESKEY.
